UNITED STATES PATENT OFFICE.

GEORGE KEPPLER, OF NEW YORK, N. Y., ASSIGNOR TO THE WESTERN CLOCK MANUFACTURING COMPANY, OF LA SALLE, ILLINOIS.

DESIGN FOR A CLOCK-STAND AND PICTURE-FRAME.

No. 39,642.

Specification for Design.

Patented Oct. 27, 1908.

Application filed August 20, 1908. Serial No. 449,569. Term of patent 7 years.

To all whom it may concern:

Be it known that I, GEORGE KEPPLER, a citizen of the United States, residing in the city of New York, borough of Manhattan, in the county and State of New York, have invented a new, original, and ornamental Design for a Clock-Stand and Picture-Frame, of which the following is a specification, reference being had to the accompanying drawing, forming a part thereof.

The figure is an elevational view of a clock stand and picture frame, illustrating my new design.

I claim:

The ornamental design for a clock stand and picture frame, as shown.

GEORGE KEPPLER.
